[57] **CLAIM**

The ornamental design for a master bed frame, as shown and described.

DESCRIPTION

FIG. 1 is a perspective front left view of our design for a master bed frame;

FIG. 2 is a perspective view which is the same as that in FIG. 1 except that the drawers on the left and right sides of the frame are pulled out;

FIG. 3 is an elevational view as seen from the front end of the frame;

FIG. 4 is an elevational view as seen from the right side of the frame;

FIG. 5 is an elevational view as seen from the rear end of the frame; and,

FIG. 6 is a top view of the frame.
